UNITED STATES PATENT OFFICE.

GEORGE OBERBECK, OF NEW YORK, N. Y., ASSIGNOR TO THE EAGLE
PENCIL COMPANY, OF NEW YORK.

DESIGN FOR A PENHOLDER.

SPECIFICATION forming part of Design No. 31,670, dated October 17, 1899.

Application filed August 1, 1899. Serial No. 725,808. Term of patent 7 years.

To all whom it may concern:

Be it known that I, GEORGE OBERBECK, residing at New York city, in the county and State of New York, have invented and produced a new and original Design for Penholders, of which the following is a specification, reference being had to the accompanying drawing, which is a plan view of a penholder, showing my new design.

As shown in the accompanying drawing, my design consists of a penholder having a series of diamond or lozenge shaped embossments *a* about the lower portion thereof and a plain reduced or tapering upper portion *b*, and beads *f* (the center one of which is most prominent) formed at the point of intersection of the plain and embossed portions and a bead *g* at the lower end of the embossments.

Having described my design, what I claim, and desire to secure by Letters Patent, is—

The design for a penholder herein described and shown.

In testimony whereof I have signed my name to this specification in the presence of two subscribing witnesses.

GEO. OBERBECK.
